UNITED STATES PATENT OFFICE.

EDWARD K. ROBINSON, OF BELMONT, MASSACHUSETTS, ASSIGNOR TO G. A. PLIMPTON, RICHARD S. THOMAS, T. B. LAWLER, AND F. C. HODGDON, ALL OF NEW YORK, N. Y., HENRY H. HILTON, DANA W. HALL, AND O. J. LAYLANDER, ALL OF CHICAGO, ILLINOIS, LEWIS PARKHURST, OF WINCHESTER, MASSACHUSETTS, C. H. THURBER, OF FRAMINGHAM, MASSACHUSETTS, SELDEN C. SMITH, OF BERKELEY, CALIFORNIA, E. A. DE WITT, OF DALLAS, TEXAS, AND L. B. ROBESON, OF ATLANTA, GEORGIA, COPARTNERS DOING BUSINESS AT BOSTON, MASSACHUSETTS, UNDER THE FIRM-NAME OF GINN & COMPANY.

BOOKBINDING.

1,148,123.

Specification of Letters Patent. Patented July 27, 1915.

Application filed June 23, 1911. Serial No. 634,956.

To all whom it may concern:

Be it known that I, EDWARD K. ROBINSON, a citizen of the United States, residing at Belmont, in the county of Middlesex and State of Massachusetts, have invented certain new and useful Improvements in Bookbinding or Book-Covers, of which the following is a specification, reference being had therein to the accompanying drawings.

10 My invention relates to the binding of books, pamphlets, catalogues, or other similar material in such a manner that the cover or binder is permanently attached to the initial contents (whether it be book, pamphlet, or catalogue, etc.), but permits of the inclusion of additional material—a pamphlet, a notebook, blank leaves, or any other similar material—in the form of a supplement to the initial contents within the same

15 cover or binder.

The purpose of my invention is to make it possible to place additional material of such nature inside of the same covers and with the original contents of a book, without breaking or tearing the binding. With the common method of binding books a few extra leaves or a pamphlet placed within the covers will ordinarily cause the binding to weaken and break.

20 In the accompanying drawings, Figure 1 is an end view of a book bound in the manner herein described, before the insertion of any supplemental matter. Fig. 2 represents a book similarly bound, to which a supplement has been added. Fig. 3 is another view of a book bound according to my invention, to which a supplement has been added. Figs. 4 and 5 show books bound in accordance with my invention, to which the

25 supplements have been attached by means of cords or wires. Fig. 6 is a detail illustrating one mode of attachment of the permanent part of the book to the cover.

In the figures, *a* represents the leaves of the book, bound together by sewing or by any of the methods commonly used by bookbinders, and attached to the back strip *b* either by being glued to the whole surface of the back strip *b* or by means of a strip

of cloth *n* attached to the leaves and also glued to the side covers, *c* and *d*. In Fig. 6 the permanent contents of the book are shown attached to the cover in both of these manners, each of which is well known to bookbinders. The cover for the book, including the sides and the back, may be one or more pieces of cloth, leather, or other material suitable for covering books. It will preferably (but not necessarily) be reinforced with board or other stiff material to form the sides of the book, *c*, *d*.

The length of the back of the cover from the point *e* to the point *f* where it is attached to the side *d*, is sufficient to permit of the attachment of the original contents to the cover and to provide in addition a strip *g*, which may be of any desired breadth. This strip *g* forms a portion of the side of the cover in the original binding of the book, but when it is desired to place additional material within the covers it may easily be bent back so that it becomes a part of the back of the book, as represented in Fig. 2, wherein *h* represents the pamphlet or extra leaves that have been added.

It will be observed that I have represented the side of the cover, *d*, as projecting slightly more beyond the leaves of the book as originally bound, than the side *c*. By this arrangement the projections *i*, *j*, of the covers beyond the ends of the leaves, will be more nearly equal when the supplement has been added. These sides *c* and *d* may however, be made of the same length or *d* may be made longer than *c*, if such arrangement is preferred in any particular case.

The supplementary matter *h* may be attached to the cover *d*, to the back *g*, or to the end paper *k* of the original contents, or to any or all of them, by any suitable device. Such attachment can be made by gluing or pasting to the cover *d*, the back *g*, (or the end paper or inside cover *k* of the initial contents) or to all of these, the covers, end papers, end tapes, or strips of cloth or any other suitable material, attached to the supplement *h*, for the purpose. The same result can be accomplished by attach-

ing a strong paper or cloth pocket or "envelop" to the cover *d*, into which may be slipped one of the covers of the supplement *h*, made of strong paper or thin board or 5 reinforced cloth or other suitable material properly cut and shaped for the purpose. This mode of attachment is represented in Fig. 3, which shows the pocket *l* attached to the original cover *d* of the book, and in this 10 pocket has been inserted the cover *m* of the supplement *h*. The supplement may be attached also by running a cord, wire, or other similar material between the middle leaves of it and around the back *g*, and securing 15 or tying it firmly to hold the contents *h* in place. Such attachment can also be made by inserting eyelets in the back strip and passing a cord through the eyelets and through the leaves of the supplement. 20 Fig. 4 shows a book bound according to my invention, to which a supplement has been added, said supplement being attached by a cord *n* running between the middle leaves of the supplement and around the 25 back of the book. Fig. 5 illustrates a book bound according to my invention, to which a supplement has been added, the supplement being attached by a cord *n* passing through eyelets *o* inserted in the back strip, 30 and through the leaves of the supplement. Likewise, holes may be punched through the side of the book and fasteners inserted through them and through holes punched in corresponding places in the supplement *h*. 35 The attachment may be made in various

other ways without departing from my invention.

The arrangement of the book cover herein described may be applied to both sides of a book; that is, the side *c*, can be made 40 like the side *d*, which would permit the addition of extra material at both the front and the back of the book.

What I claim as new, and desire to secure by Letters Patent is:

1. A permanently bound book having the permanent contents thereof attached to both of the side covers, a back for the permanent contents of the book, and a strip of material connected flexibly to the back and one 50 side cover, said strip being adapted to serve normally as a part of the side cover, and when a supplement is added to the book, as a back for such supplement.

2. A permanently bound book having a 55 back to which the permanent contents of the book are bound, and side covers, one of which is connected to the back by a strip of material adapted to serve as part of the side cover until a supplement is added to 60 the book and then to serve as a back for such supplement.

In testimony whereof, I have hereunto subscribed my name this 22d day of June, 1911.

EDWARD K. ROBINSON.
